Application November 3, 1932. Serial No. 45,721

Term of patent 14 years

To all whom it may concern:

Be it known that HENRY M. ROSENDAL DAM, a citizen of Denmark and resident of Floral Park, L. I., in the county of Queens and State of New York, has invented a new, original, and ornamental Design for a Decorative Illuminating Unit of which the following is a specification, reference being had to the accompanying drawing, forming part thereof, in which,

Fig. 1 is a front elevational view of a decora-

tive illuminating unit embodying my new design adapted for example to be positioned on the top of a Christmas tree.

Fig. 2 is an end elevational view thereof.

I claim:

The ornamental design for a decorative illuminating unit, substantially as shown.

Dated, October 27th, 1932.

HENRY M. ROSENDAL DAM.
